UNITED STATES PATENT OFFICE.

CHARLES M. TILLMANN, OF CHICAGO, ILLINOIS.

BOTTLE-CARRIER.

1,274,631.

Specification of Letters Patent. Patented Aug. 6, 1918.

Application filed May 3, 1917. Serial No. 166,234.

To all whom it may concern:

Be it known that I, CHARLES M. TILLMANN, a citizen of the United States, residing at Chicago, in the county of Cook and State of Illinois, have invented certain new and useful Improvements in Bottle-Carriers, of which the following is a specification.

This invention relates to new and useful improvements in carriers for articles such as water bottles or other liquid containers.

One of the principal objects of the invention is to provide a carrier formed from a minimum amount of stock and constructed to permit a bottle being readily positioned in the carrier, or removed therefrom and to retain the bottle against accidental displacement while being carried.

Another important object of the invention is to provide a bottle carrier of the character described, which is mainly constructed from a plurality of long lengths of wood fiber, such as reeds or the like.

A still further object of the invention is to provide a carrier having a partially woven wall for retaining the bottom of the bottle against displacement, and completing the wall with a name place, whereby, should the plate be surreptitiously removed, the act will be readily apparent by viewing the incomplete retaining wall.

These and other objects will in part be obvious, and will be hereinafter more fully disclosed.

In the drawings, which show by way of illustration one embodiment of my invention,

Figure 1 is a front elevation of the carrier;

Fig. 2 is a side elevation thereof;

Fig. 3 is an enlarged horizontal sectional view taken on the line 3—3 of Fig. 2, and

Fig. 4 is a detail vertical sectional view taken on the line 4—4 of Fig. 3.

Like reference numerals designate corresponding parts in all the figures of the drawings.

Referring specifically to the construction shown in the drawings, 5 designates a base, which, in this instance, is circular in outline, and is formed from wood. Extending upwardly from and connected to said base is a handle, which, in this instance, is composed of two reeds 6 and 7 respectively. These reeds are bent into an inverted U-shaped formation, and one end 7^a of the reed

7 is bent at right angles and fitted into a corresponding opening 5^a formed in the wall of the base 5. One end of the reed 6 is likewise bent, as at 6^a, and is fitted into a corresponding opening 5^b formed in the wall of the base 5, and at a point diametrically opposite the opening 5^a. These ends 6^a and 7^a of said reeds are preferably secured to the base by nails or other suitable means. The other end of the reed 7 extends downwardly alongside of the reed 6, as clearly shown in Fig. 3, and the other end of the reed 6 extends down along the other side of the reed 7 as clearly shown in said figure. It will thus be noted that the free ends of the reeds 6 and 7 respectively extend on opposite sides of a line extending through the end portions 6^a and 7^a of said reeds. By this construction, the two reeds which form the handle may be readily centered. The free ends of the reeds are secured to the side wall of the base by nails or the like. By inserting one end of each reed in an opening as above described, the handle is thereby firmly secured to said base.

Secured to the side wall of the base, and extending upwardly therefrom for a short distance, is a series of pegs 8. A plurality of reeds 9 are interwoven with the pegs 8 to form an outwardly extending flange. These reeds 9 are only woven with the pegs at the upper ends of the latter so as to leave an incomplete retaining wall for the lower end of the bottle which is seated therein.

The marginal wall, which has been described so far as being formed by the pegs and reeds 9, is completed by one or more name plates 10 which may be secured to the base 5 and pegs 8 by any suitable means.

The bight 11 of the handle is disposed a considerable distance above the mouth of the bottle and in order to provide a means for retaining the upper end of the bottle against accidental displacement and yet permitting of said bottle to be readily placed in the carrier, or removed therefrom, I have provided a retaining annulus which is indicated as a whole by the numeral 12. In this instance the annulus is formed by two reeds 13 and 14. The central portion of each of these reeds 13 and 14 is bent into looped formation, and these loops are interlaced to form the annulus. The ends of the respective reeds are twisted in opposite directions as at 13^a and 14^a, and then fixedly

secured to the legs of the handle. It is disposed in a horizontal plane at a point considerably below the bight 11 of the handle and at a point considerably above the marginal wall of the base. By forming the opposite twists 13^a and 14^a, the annulus will be always returned to its normal horizontal plane, should the same become distorted when placing or removing the bottle. It will be noted that the space between the annulus and the bight 11 of the handle is sufficient to permit the bottle to be elevated until the lower end thereof can be swung outwardly above the marginal wall of the base. This action will, of course, swing the annulus into an inclined plane, but as soon as the bottle has been seated, or removed, as the case may be, the annulus will return to its normal horizontal plane.

Should any user surreptitiously remove the name plate or plates 10, the retaining wall will, of course, present an unfinished appearance, and will readily indicate that a name plate has been removed.

It is obvious that minor changes in the details of construction or the arrangement of parts may be made without departing from the spirit of the invention.

Having thus described my invention, what I claim is:

1. A carrier having a U-shaped handle and an article support at its lower end, said support comprising a base having a marginal wall for retaining the article against displacement, said wall comprising a plurality of vertically disposed pegs connected at the outer edge of said base, a plurality of reeds interwoven with and connecting the upper ends of said pegs and forming a relatively narrow edging for the upper edge of the wall, and a covering for the remainder of the wall formed from a relatively wide strip of sheet material, said strip being disposed between the base and the edging

Copies of this patent may be obtained for five cents each, by addressing the "Commissioner of Patents, Washington, D. C."

and directly below the latter and wholly 45 against the outer faces of said pegs.

2. In a carrier for containers, the combination with a base having a marginal wall for retaining the lower end of the container against displacement, of an inverted U-shaped handle connected at its ends to said base at substantially diametrically opposite points thereof, and an annulus supported by said handle and disposed in a plane above and in spaced relation to said marginal wall 55 for receiving the upper end of the container and retaining the latter against accidental displacement, said annulus being formed from two fiber reeds, each reed being centrally looped and interlaced one with the other, the free ends of the respective reeds being secured to the legs of the handle.

3. In a carrier for containers, the combination with a base having a marginal wall for retaining the lower end of the container 65 against displacement, of an inverted U-shaped handle connected at its ends to said base at substantially diametrically opposite points thereof, and an annulus supported by said handle and disposed in a plane 70 above and in spaced relation to said marginal wall for receiving the upper end of the container and retaining the latter against accidental displacement, said annulus being formed from two fiber reeds, each reed being 75 centrally looped and interlaced one with the other, the free ends of the respective reeds being secured to the legs of the handle, said reeds between said annulus and said legs being oppositely twisted to retain said 80 annulus in a horizontal plane.

In testimony whereof I affix my signature in the presence of two witnesses.

CHARLES M. TILLMANN.
